SOCKET WRENCH HAVING NUT-RETAINING MEANS

Walter E. Hubbard, Indianapolis, Ind., assignor to Western Electric Company, Incorporated, New York, N. Y., a corporation of New York

Application May 27, 1954, Serial No. 432,678

1 Claim. (Cl. 81—125)

This invention relates to socket wrenches having nut-retaining means, and has for an object thereof the provision of new and improved socket wrenches.

Another object of the invention is to provide socket wrenches which may be easily maintained.

A further object of the invention is to provide socket wrenches having spring article-holding elements which are not permanently fixed to the wrenches.

A socket wrench illustrating certain features of the invention may include an element having a head provided with a socket for receiving a nut or the like and a shank portion. Slots disposed radially in the head and the shank portion serve to receive wire springs provided with hooked ends entering bores in the shank portion of the element, and a sleeve mounted slidably on the shank portion may be moved between positions in which the springs may be removed from the element and positions in which the springs are locked in the slots to grip a nut positioned in the socket.

A complete understanding of the invention may be obtained from the following detailed description of a socket wrench forming a specific embodiment thereof, when read in conjunction with the appended drawings, in which:

Fig. 1 is a vertical section of a wrench forming one embodiment of the invention;

Fig. 2 is an enlarged fragmentary view of a portion of the wrench shown in Fig. 1, parts being broken away and shown in section, and

Fig. 3 is a further enlarged, horizontal section taken along line 3—3 of Fig. 2.

Referring now in detail to the drawings, there is shown therein a wrench for picking up nuts 10 and threading them onto studs or the like. The wrench includes a body 11 having a shank 12 and a head 13 having a hexagonal socket 14 therein which is slightly larger than the nuts 10. A driver 16, which may be power driven or manually driven, is connected by a pin 17 to the shank 12. A retaining sleeve 18 is mounted slidably on the shank 12, and when in the upper position, as shown in Fig. 1, it permits wire springs 20 to be removed and replaced. When moved to the lower position thereof as shown in Fig. 2, the retainer presses against the springs 20 to hold end rings 22 tightly against the nut 10 so that the nut then may be lifted and held in the socket 14.

2

The springs 20 lie in grooves 24' and slots 24 and tang or hook portions 25 fit loosely into bores 26 to support the springs from the body 11. The springs also fit loosely with respect to the grooves 24' and the slots 24 so that they may freely spring out of the slots 24, as the sleeve 18 is retracted, or may be freely cammed into the slots, as the sleeve is moved down. The clearance between each of the hook portions 25 and the rings 22 in the bores 26 and the slots 24 is such that only limited turning action of the springs is possible so that when the sleeve 18 is moved to its lowermost position, the rings 22 are pressed tightly against the nuts 10.

After the nuts 10 are threaded onto the article, the wrench may be pulled upwardly off the nut 10 without moving the sleeve 18. Likewise, the wrench need only be pressed over the nut 10 to pick it up, the rings 22 being sprung outwardly by a camming action of the nut 10 that is being pressed into the socket 14.

The above-described wrench is very simple in operation and construction, and may be easily maintained merely by sliding the sleeve 18 upwardly to replace the springs 20.

It is to be understood that the above-described arrangements are simply illustrative of the application of the principles of the invention. Numerous other arrangements may be readily devised by those skilled in the art which will embody the principles of the invention and fall within the function and scope thereof.

What is claimed is:

30 A socket wrench for holding an article forced into the socket, which comprises a body provided with a head portion having a socket therein and a shank portion, said body being provided with radial slots spaced circumferentially 120° and extending from the exterior of the head portion to the interior thereof and merging into grooves extending along the exterior of the shank portion and said body being provided with a bore positioned in the shank portion at the end of each groove, a plurality of wire springs each provided with a hook portion disposed in one of the bores in the shank and a rounded article-engaging portion disposed in one of the radial slots, said rounded article-engaging portions being movable partly into the socket in the head and yieldably held therein, and spring-retaining means mounted on the shank for pressing the wire springs into the grooves so as to force the article-engaging portions thereof partly into the socket.
